PNEUMATIC TIRE TREAD AND BUTTRESS COMBINATION

Arthur C. Blankenship, Detroit, Mich., assignor to
Uniroyal, Inc., New York, N.Y.

Filed Nov. 23, 1971, Ser. No. 201,630

Term of patent 14 years

Int. Cl. D12—15

U.S. Cl. D90—20 R

FIG. 1 is a perspective view, partly schematic, of a pneumatic tire tread and buttress combination embodying my new design, it being understood that the pattern is repeated throughout the circumference of the tread and buttress, as shown schematically by solid lines, and that the buttress combination pattern is repeated on the opposite side. For convenience of illustration, applicant has omitted from FIG. 1 the representation appearing in FIG. 3 which extends axially inwardly from the lower external edges of the buttress.

FIG. 2 is an enlarged, fragmentary developmental plan view of the tread and buttress combination of FIG. 1;

FIG. 3 is a sectional view of the tread and buttress combination, taken substantially as indicated by line 3-3 of FIG. 2;

FIG. 4 is an enlarged, fragmentary sectional view of the buttress, taken substantially as indicated by line 4-4 of FIG. 2; and

FIG. 5 is an enlarged, fragmentary sectional view of the buttress, taken substantially as indicated by line 5-5 of FIG. 2.

I claim:

The ornamental design for a pneumatic tire tread and buttress combination, substantially as shown and described.
